PRINTED TEXTILE FABRIC

Dorothy Burns, New York, N. Y.

Application September 15, 1955, Serial No. 37,945

Term of patent 3½ years

(Cl. D92—1)

The figure is a plan view of a piece of printed textile fabric, showing my new design.

My design consists of a series of printed lace-effect stripes separated by three stripes which are graduated as to thickness and color tone, each alternate lace-effect stripe being flanked by a narrow stripe of the lightest tone, and the other lace-effect stripe flanked by a wide stripe of the darkest tone; a stripe of intermediate width and tone lying between the light and dark toned stripes, all as shown.

I claim:

The ornamental design for a printed textile fabric, as shown and described.
